UNITED STATES PATENT OFFICE

ALBERT BODMER, OF WATTWIL, SWITZERLAND, ASSIGNOR TO HEBERLEIN & CO., A. G.,
OF WATTWIL, SWITZERLAND, A CORPORATION OF SWITZERLAND

DYEING

No Drawing. Original No. 1,694,526, dated December 11, 1928, Serial No. 121,736, filed July 10, 1926, and in
Germany July 14, 1925. Application for reissue filed September 14, 1929. Serial No. 392,749.

My invention relates to improvements in
dyeing and more particularly the main object
of the invention is to provide an improved
method for treating cellulosic fibers or fab-
rics to render the same relatively immune to
5 substantive dyestuffs and also certain novel
products which may be produced with the aid
thereof. Further and more specific objects,
features and advantages will more clearly ap-
pear from the detailed description given be-
10 low in which preferred forms of the invention
are fully set forth.

Heretofore certain methods have been pro-
posed for changing the dyeing properties of
15 vegetable or cellulosic fibers by way of acetyl-
ating, benzoating or the like, but these meth-
ods have certain disadvantages. According
to the present invention in its preferred form
the vegetables or cellulosic fibers or fabric
20 are treated with a phosphorous halogen com-
pound whereby novel and valuable products
are obtained. If the material is treated with
alcoholic caustic alkali in connection with the
treatment with the phosphorous halogen
25 compound the material becomes immune to
substantive dyes and has as well an affinity
for basic dyestuffs. If the caustic is employed
in water solution, for example as a water
paste in printing, the immunity to substan-
30 tive dyestuffs is not satisfactory although an
increase in the affinity for basic dyestuffs does
occur. In addition to purely inorganic phos-
phorous halogen compounds such as phos-
phorous trichloride, phosphorous oxychloro-
35 ride, etc. organically substituted phosphorous
halogen compounds such as ethyl-phospho-
oxy-chloride and other phosphorous com-
pounds such as triphenyl-phosphate may be
used with more or less success.

40 For the purpose of rendering the cellulose
fibers immune to substantive dyestuffs and
increasing their affinity for basic dyes, cotton
yarn is immersed in a solution of caustic soda
in alcohol, containing 10% of caustic soda by
45 weight, to alkalize the cellulosic fibers thereof
in a manner well understood by those skilled
in the art, and after removing the yarn from
the solution the excess of solution is squeezed
out of the same. The yarn thus prepared is
50 then brought into a solution of phosphor-

ous trichloride in xylol containing 200 grams
of phosphorous trichloride per liter of
xylol. Thus the cotton fibers of the yarn
are treated with the phosphorous halogen
compound in the presence of some alkali 55
which remains on the yarn from the alkalin-
izing treatment. When the yarn is thus treat-
ed with the phosphorous trichloride solution
the reaction takes place after a short time,
with development of heat. The yarn is then 60
thoroughly washed, soaped and dried and it
is found that the fibers have lost their affinity
for and are substantially immune to substan-
tive dyestuffs while they have acquired a pro-
nounced capacity for dyeing with basic dye-
65 stuffs without previous mordanting.

The yarn so treated may be woven together
with ordinary cotton yarn or untreated cel-
lulosic threads to form a fabric and remains
in the fabric as a white effect when the
70 fabric is dyed with substantive dyestuffs.
If desired, the yarn before the treatment with
the phosphorous compound, may be colored,
as for example with substantive dyestuff, and
then rendered immune to further dyeing with
75 substantive dyestuffs by the treatment as
above described and then the yarn woven
together with untreated cotton yarn or cel-
lulosic threads, and the fabric treated with a
substantive dyestuff of a different color, 80
whereupon the threads which have been treat-
ed with the phosphorous compound will re-
main of a different color from those which
were untreated with the phosphorous com-
pound. The reaction of the phosphorous 85
halogen compound on the cellulose appears
to set free halogen acid and the presence of
alkali on the goods will serve to remove such
acid by neutralizing the same thus preventing
its injuring the goods. The phosphorous 90
I believe combines with the cellulosic material
to form a phosphorous cellulose compound
which is relatively resistant and immune to
substantive dyestuffs and relatively attrac-
tive to basic dyestuffs, generally speaking. 95

Instead of treating the yarn before it is
woven into fabric, a woven fabric made of
cotton or cellulosic fibres may be first treat-
ed with an aqueous caustic alkali solution in
the well known way to alkalize the cellulose 100

thereof and then the excess alkali solution squeezed out and the fabric passed through a 10% solution by weight of phosphorous oxychloride in benzol. Various other hydrocarbon solvents may be used for producing the solution of the phosphorous compound or compounds. After completion of the reaction the material may be washed and may then be dyed with basic dyestuffs without previous mordanting.

10 The invention may be applied not only to ordinary cotton fibers and fabrics but also to artificial silk fibers and fabrics, such as artificial silk made from regenerated cellulose, e. g. hydracellulose such as viscose, cupra ammonia cellulose and collodion silk. Such artificial silk may be treated with the phosphorous halogen compounds or the like and alcoholic caustic alkali, and it will then be 15 found to have become substantially immune to substantive dyestuffs and to have acquired an affinity and attraction for basic dyestuffs. If these silks are treated with water solutions of caustic alkali or with water paste containing 20 caustic alkali, they acquire an affinity for basic dyes, but they do not acquire a satisfactory immunity to substantive dyes. Therefore, by cellulosic fibers, and fabrics or material I intend to include all such artificial 25 silk as well as other cellulosic material. With artificial silks which consist of cellulose esters or cellulose ethers, e. g. acetate silk, and which repel most of the common dyestuffs, their affinity for basic dyestuffs becomes 30 marked when treated in the manner described.

The treatment with alkali may be applied 35 after instead of before the treatment with the phosphorous compound. Thus it is not necessary that the cellulosic material be treated 40 with the phosphorous compound in the presence of the alkali and the cellulosic material may be washed with water or with an inert solvent and dried, if desired, between the two treatments. Also in many cases the 45 alkali treatment may be omitted altogether and substantially the same results obtained, as obtained by the use of water solution of caustic alkali.

50 The cellulosic material may be directly treated with the phosphorous compound, and without any treatment with alkali, and there may, according to the concentration, be embodied in the fiber or added to the solution 55 to neutralize the acid liberated in the reaction, acid binding or removing bodies such as sodium bicarbonate, calcium carbonate and the like. This method is also not only applicable to the natural cellulose fibers but 60 also to the artificial silks and the like, and results in increasing their affinity for basic dyes.

White and colored or two colored effects 65 may also be produced in a fabric by the local application or treatment to render certain

portions of the cellulosic material immune to substantive dyestuffs and attractive to basic dyestuffs according to any predetermined design. Thus a reserve thickening or paste may be printed upon the fabric according to the predetermined design and then the fabric treated with the phosphorous compound solution either with previous alkalization or subsequent alkalization or without the same. If the alkali treatment is a treatment with alcoholic caustic alkali immunity to substantive dyes and increased affinity for basic dyes result. If a water solution of caustic alkali is employed or if the caustic alkali is omitted, a satisfactory immunity to substantive dyes is not obtained, but an increased affinity for basic dyestuffs occurs. If desired the alkalization of the fiber may be accomplished by printing a thickened alkali directly on the fabric in accordance 70 with a predetermined design and then the local chemical changes brought about by immersion of the fabric in the solution of phosphorous compound and if desired a dyestuff may be printed on the fabric at the same 75 time with the thickened alkali, or a thickened solution of the phosphorous compound may be printed on the fabric according to 80 a predetermined design.

Thus the process may be used for the production of new materials of natural vegetable or artificial fibers, with pattern effects by the local application of the phosphorous compound by printing or applying the same 85 in accordance with any predetermined design, whereupon the portions so acted upon by the phosphorous compound will be particularly resistant to substantive dyestuffs and relatively attractive to basic dyestuffs 90 or simply have increased affinity for basic dyes alone, and upon subsequent dyeing, 95 clouded or other variegated effects may be produced. While a phosphorous chlorine compound is preferred, nevertheless other halogens and other compounds of phosphorus may be used with more or less success.

100 While I have described my improvements in great detail and with respect to preferred forms thereof, I do not desire to be limited to such details or forms since many modifications and changes may be made and the invention embodied in widely different forms 105 without departing from the spirit and scope thereof in its broader aspects. Hence I desire to cover all modifications and forms 110 coming within the language or scope of any one or more of the appended claims.

115 What I claim as new and desire to secure by Letters Patent, is:

120 1. Method of modifying the dying properties of cellulosic fibers which consists in treating the fibers with alcoholic caustic alkali and acting on the same with a compound of the class consisting of phosphorous halogen compound and triphenyl-phosphate 125 130

capable of making the cellulosic fibers relatively immune to substantive dyestuffs and relatively attractive to basic dyestuffs.

2. Method of modifying the dying properties of cellulosic fibers which consists in treating the fibers with alcoholic caustic alkali and acting on the same with a phosphorous halogen compound capable of making the cellulosic fibers relatively immune to substantive dyestuffs and relatively attractive to basic dyestuffs without previous mordanting.

3. Method of modifying the dying properties of cellulosic fibers which consists in treating the fibers with alcoholic caustic alkali and treating the fibers with a phosphorous halogen compound sufficiently to make the fibers relatively immune to substantive dyestuffs and relatively attractive to basic dyestuffs and removing the halogen acid formed.

4. A cellulosic fiber containing phosphorus capable of substantially resisting substantive dyestuffs and attracting basic dyestuffs, so that when the fiber is treated with substantive dyestuffs, it remains substantially uncolored thereby.

5. Method of modifying the dyeing properties of cellulosic fibers which consists in treating the same with a phosphorous halogen compound in the presence of an alcoholic solution of a caustic alkali material.

6. Method of making fabrics with variegated colored effects which consists in forming the fabric with cellulosic threads, some only of which have been treated with a compound of the class consisting of phosphorous halogen compounds and triphenyl-phosphate capable of rendering them relatively immune to substantive dyestuffs whereby when the fabric is treated with substantive dyestuffs the so treated threads remain substantially unaffected.

7. Method of making fabrics with variegated colored effects which consists in forming the fabric with cellulosic threads, some only of which have been first colored and then treated with a compound of the class consisting of phosphorous halogen compounds and triphenyl-phosphate to render them relatively immune to substantive dyestuffs whereby when the fabric is treated with substantive dyestuffs the so treated threads remain substantially unaffected.

8. In the method of producing colored designs on fabrics which step consists in taking a fabric of cellulosic threads and treating the same according to a predetermined design with a compound of the class consisting of phosphorous halogen compounds and triphenyl-phosphate, and an alcoholic caustic alkali solution, whereby the cellulosic fiber at the places so treated is rendered relatively immune to substantive dyestuffs and relatively attractive to basic dyestuffs.

9. A fabric of cellulosic threads having certain portions thereof treated according to a predetermined design with a phosphorous halogen compound rendering the fiber of such treated portions substantially immune to substantive dyestuffs and relatively attractive to basic dyestuffs without the previous use of a mordant whereby when the fabric is treated with substantive dyestuffs the so treated threads remain substantially unaffected.

10. Threads of cellulosic material containing phosphorous whereby the threads are rendered substantially immune to substantive dyestuffs, so that when the threads are treated with substantive dyestuffs they remain substantially uncolored thereby.

11. Method of producing variegated designs on fabrics of cellulosic material which consists in printing a paste reverse material on the fabric according to a predetermined design and exposing the fabric to the action of a phosphorous halogen compound locally according to said design.

12. Method of modifying the dyeing properties of cellulosic fibers which consists in treating the fibers with a compound of the class consisting of phosphorous halogen compounds and triphenyl-phosphate capable of making the cellulosic fibers substantially immune to substantive dyestuffs and relatively attractive to basic dyestuffs and also treating with an acid binding material, so that when the fibers are treated with substantive dyestuffs they remain substantially uncolored thereby.

13. Method of modifying the dyeing properties of cellulosic fibers which comprises treating the cellulosic fibers with alcoholic caustic alkali, introducing the material thus treated into a solution of a compound of the class consisting of phosphorous halogen compounds and triphenyl-phosphate and allowing reaction between said compound and the material to occur whereby the material to occur whereby the material is rendered practically immune to substantive dyestuffs and has an increased affinity for basic dyes.

14. A method of producing variegated designs on a fabric of cellulosic material which comprises printing a reserve on the fabric according to a predetermined design, treating the fabric with alcoholic caustic alkali solution, treating the fabric with a solution of a compound of the class consisting of phosphorous halogen compounds and triphenyl-phosphate whereby the unprinted portions of the fabric are rendered immune to substantive dyestuffs and have an increased affinity for basic dyestuffs, removing the reserve and dyeing the fabric to reproduce the design printed thereon.

15. A cellulosic fiber in which at least some of the cellulose has been subjected to

caustic alkali deposited thereon from an alcoholic solution and to a phosphorous halogen compound, and which is relatively more resistant to substantive dyestuffs and more attractive to basic dyestuffs.

5 16. A fabric of cellulosic threads having certain portions thereof treated according to a predetermined design with a phosphorous halogen compound in the presence of a 10 caustic alkali deposited thereon from an alcoholic solution of said alkali rendering the fiber of such treated portions relatively resistant to substantive dyestuffs and relatively attractive to basic dyestuffs.

15 17. Artificial silk fiber of regenerated cellulose in which at least some of the fiber has been subjected to a caustic alkali material deposited thereon from an alcoholic solution and treated with a phosphorous halogen compound, the fiber being relatively immune to substantive dyestuffs and relatively attractive to basic dyestuffs.

20 In testimony whereof, I have signed my name to this specification.

25 ALBERT BODMER.
